Primary Examiner — Antoine D Davis(74) *Attorney, Agent, or Firm* — Gregory W. Smock(57) **CLAIM**

The ornamental design for the mirror image drilling jig, as shown and described.

DESCRIPTION

FIG. 1 is a front perspective view of the mirror image drilling jig;

FIG. 2 is a side view of the mirror image drilling jig;

FIG. 3 is a rear perspective view of the mirror image drilling jig;

FIG. 4 is a front view of the mirror image drilling jig;

FIG. 5 is a rear view of the mirror image drilling jig;

FIG. 6 is a top view of the mirror image drilling jig; and,

FIG. 7 is a bottom view of the mirror image drilling jig. The broken line showing of structural features is included for the purpose of illustrating non-claimed subject matter and forms no part of the claimed design.
